GEORGE MERRILL, OF NEWBURYPORT, MASSACHUSETTS, ASSIGNOR TO
SAMUEL BLISH, OF PISCATAWAY, NEW JERSEY.

Letters Patent No. 82,430, dated September 22, 1868.

IMPROVEMENT IN CARVING-MACHINES.

The Schedule referred to in these Letters Patent and making part of the same.

TO ALL WHOM IT MAY CONCERN:

Be it known that I, GEORGE MERRILL, of Newburyport, in the county of Essex, and State of Massachusetts, have invented certain new and useful Improvements in Carving and Cutting Type from Patterns; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention relates to improvements in machines for cutting wooden type; and consists in a novel arrangement of the cutting-tool and guide, and in a peculiar arrangement of sliding tables and levers, by which the size of the letter being cut can be made greater or less than the pattern, to any degree desired.

The drawing represents my machine in perspective, ready for use.

In constructing my improved machine, I provide a suitable bed or frame, A, having an upright or standard, B, at its rear end. A sliding bed or table, D, is mounted on this frame A, and arranged to slide to and fro with accuracy thereon. This bed D has side-pieces, H, projecting vertically, with horizontal arms, l, projecting to a distance equal to the length of the bed, or more, as represented in the drawing.

Upon these arms l is mounted another bed or table, P, which has a vertically-projecting arm, t, on one side, as shown; this upper bed thus resting and sliding on the lower one, or, rather, on the frame attached to the lower one.

A horizontal arm, C, projects from the top of the upright, B, in a diagonal position, so as to bring its outer end even with the side of the tables P and D, the arm C being secured rigidly in position, and having pivoted to its end a vertical lever, h, which is connected to the upper table by a rod, n, and to the lower table by a rod, m, these rods n and m being pivoted at each end, so as to permit the parts to move freely.

In front of the upright, B, is mounted a vertical rod or shaft, I, loosely, so that it can turn horizontally, and also move vertically, it resting on a spring, f, which allows it to be pressed down when desired. To this shaft I are attached rigidly two horizontal arms, a and b, the former projecting out over the table D, and the latter over the other table P.

In the outer end of the arm a is mounted a spindle, having a pulley, u, on it, into which spindle the cutting-tool d is inserted; this pulley u being driven by a belt, v, passing around a drum or pulley, E, placed vertically behind the upright, B.

Upon the upper arm, b, is secured a sliding clamp, having the guide or pointer c attached, this clamp being arranged to slide to and fro on the arm b, and having a thumb-nut to secure it in place, as shown.

In operation, the pattern is placed on the table P, and the block to be cut is placed on the table D. The arm b is then brought down, so as to press the guide or pointer c upon the pattern, which movement presses the cutter d down upon the block on the table below, and as the arm b is moved laterally, to follow the form of the pattern, it causes the tool d to make the same or corresponding movements on the block below.

By changing the points at which the connecting-rods n and m are attached to the lever h and the tables, the ratio of movement between the tables may be varied at will.

When attached as represented in the drawing, the lower rod, m, is twice as far from the fixed point o as the rod n is, and, consequently, when the lower end of the lever h is moved to or fro, the lower table, D, will be moved twice the distance that the other table will be, thus making the letter cut of double the size of the pattern. In order to produce a corresponding variation in the size laterally, the pointer should be adjusted on the arm b at a relatively-corresponding distance from the shaft I.

If it be desired to reverse the operation, and cut a letter or figure smaller than the pattern, the shaft I can be turned upside down, thus bringing the guide-arm b over the lower table, and the tool-arm a over the upper table, the guide-pointer c and the tool d being also reversed or turned upside down, to bring them into

proper position for operation. In such case, of course, the belt will necessarily be moved with-arm *a*, and be above the upper table, the pulley or drum *E* being made long enough to permit the belt to be slipped up to that position.

It is obvious that, by altering or adjusting the relative position of the cutter and the guide, and also the points of connection between the lever *h* and the tables, a great variety of changes may be made between the size of the letter cut and the pattern.

It is also obvious that the upper table may be made to rest on a rigid frame, attached to the main frame, *A*, instead of being attached to the lower table, and the result still be the same.

In case it be desired to cut the figure of the same size as the pattern, one of the rods *n* or *m* will be detached, and the two tables secured to each other, so as to move together.

The tables may be moved by rack and pinion, or any other suitable means, the object of the lever *h* and rods *n* and *m* being simply to regulate their movements relatively to each other.

It is obvious that instead of arranging the tables one above the other, they may be arranged side by side, in which case, the lever *h* and the connecting-rods would be placed horizontally instead of vertically, as would also the arms *a* and *b* of the shaft *I*, the operation and result being precisely the same, as already described.

Having thus described my invention, what I claim, is—
1. The combination of the tables *D* and *P*, connected by links or rods *n* *m* to the lever *h*, substantially as described.

2. The shaft *I*, mounted in the main frame, and provided with the rigid arms *a* and *b*, carrying the adjustable guide *c* and the cutter *d*, and arranged, in relation to the tables *D* and *P*, substantially as described.

3. The table *D*, provided with the side-pieces or frame *H* *l* for supporting the upper table *P*, and permitting the latter to be moved thereon, as herein described.

GEO. MERRILL.
